DESIGN FOR A DESK

Elmer H. Daniels, West Los Angeles, Calif., assignor to Jasper Desk Company, Jasper, Ind., a corporation of Indiana

Application February 15, 1945, Serial No. 117,983

Term of patent 7 years

(Cl. D33—7)

To all whom it may concern:

Be it known that I, Elmer H. Daniels, a citizen of the United States, residing at West Los Angeles, county of Los Angeles, State of California, have invented a new, original, and ornamental Design for Desk, of which the following is a specification, reference being had to the accompanying drawings, forming a part thereof.

In the drawings—

I claim:

The ornamental design for a desk, substantially as shown.

ELMER H. DANIELS.
